Primary Examiner — L. A. Grabenstetter(74) *Attorney, Agent, or Firm* — Birch, Stewart, Kolasch & Birch, LLP(57) **CLAIM**

The ornamental design for a monitor, as shown and described.

DESCRIPTION

1. Monitor

1.1 : Perspective

1.2 : Front

1.3 : Back

1.4 : Left

1.5 : Right

1.6 : Top

1.7 : Bottom

1.8 : Partial enlarged perspective

Reproduction 1.8 is an enlarged view showing a portion of the control box at the bottom of the display panel; the oblique shading lines in reproductions 1.1, 1.2 and 1.8 are used to show the display screen of the claimed design, and do not represent its surface ornamentation.

The dash-dash broken lines depicting portions of the monitor represent features that form no part of the claimed design. The dot-dot-dash broken lines forming a rectangle in
